(57) CLAIM

The ornamental design for a utensil for a toddler, as shown and described.

DESCRIPTION

FIG. 1 is a perspective view of a utensil for a toddler design; FIG. 2 is a front elevational view thereof; FIG. 3 is a rear elevational view thereof; FIG. 4 is a left side view thereof; FIG. 5 is a right side view thereof; FIG. 6 is a top plan view thereof; and, FIG. 7 is a bottom plan view thereof.

The broken lines showing portions of the utensil for a toddler design in FIGS. 1-7 are for illustrative purposes only and form no part of the claimed design.
